TELEGRAPH KEYBOARD APPARATUS

Ronald George Griffith, Upper Warlingham,
EnglandApplication July 25, 1935, Serial No. 33,144
In Great Britain November 26, 1934

14 Claims. (Cl. 178—79)

This invention relates to keyboard controlled telegraph apparatus in which a number of keybars are arranged so that by their movements they effect telegraphic transmission or perforation of code permutations or both.

Owing to the growing demand that the operation of telegraph keyboard apparatus shall not require any special skill, beyond that expected of a typist, the present trend in design of such apparatus is to produce telegraph keyboard instruments which are similar in operation as far as is possible to that of a standard typewriter. In the standard typewriter mechanism, certain numerals or other symbols are carried on the same type levers as letter characters so as to be operated under the control of a single key, the particular character which is printed being selected by the shift mechanism of the typewriter. In order to establish a similar operating condition for a telegraph keyboard when using a telegraph signalling code in which different code permutations are allotted to letter characters and numerals or other symbols, which in the case of a typewriter are carried on the same type lever, it is necessary to provide mechanism so that the depression of a single key-bar may produce different code permutation settings as selected by the shift mechanism similar in operation to that of a standard typewriter. Furthermore, at certain speeds, on depression of the key-bars of a typewriter it only requires partial depression in order to print satisfactorily and the kinetic energy of the type lever produces a certain reaction. These features produce a reaction in the operation of the typewriter generally called the "touch" and it is very desirable that the touch of a telegraph keyboard apparatus should be similar to that of a typewriter.

Thus, the present invention aims at providing a keyboard controlled mechanism for setting up code permutations and, in fact, a mechanism, the touch of which can, if desired, be made similar to that of a typewriter. The object of the invention is further to enable certain of the individual keybars of a keyboard selectively to set up one of two different code permutations on one and the same set of permutation members. Further, the invention has the purpose of enabling the permutation settings to be established by power-driven mechanism operating selectively under the control of the keybars.

Thus, according to the present invention, the permutation members of the mechanism for setting up the code permutations are pivoted members such as vanes and are arranged to be posi-

tively and selectively set in position by any or all of a number of permutation setting members by direct action of the latter on the permutation members on either side of their pivots. Thus, the permutation setting members may be slidably mounted frames which engage with the pivoted vanes by means of internal notches or projections on the frames. Furthermore, a number of keybars may be mounted and arranged so that when depressed, each sets up a permutation setting used for telegraphic transmission or perforation or both, and each of the keybars also acts upon one of a number of permutation selecting members which can be set selectively in one of two positions through the agency of the shift mechanism. When the common pivot of the selector members is in one of its two positions, each selector member is mechanically coupled to one of the permutation setting frames, but when the common pivot is moved by the shift key into its other position, some of the selector members are mechanically coupled to different permutation setting frames, being disengaged from those frames with which they were previously coupled when the common pivot was in the first or normal position. The depression of any key-bar of the number referred to, effects the permutation setting of the permutation setting member to which the selector member allocated to that key is at that time coupled.

In other words, the depression of each character key causes the sliding movement of one or the other of two permutation frames depending upon the position of the shift mechanism at that time. Each of these frames, forming the permutation setting members, when moved sets the code permutation peculiar to the character of the keybar depressed. Conveniently projections on the sliding frames may turn vanes on spindles which extend so far as to carry further vanes engaging projections on further permutation frames, of which there are five, when working on the five-element code, the result being that these five last-mentioned frames take up positions corresponding to the permutation to be set.

Instead of the keybars acting with a direct mechanical connection to the permutation setting frames, it may be arranged that each keybar when depressed moves an interposed member which is then clutched to a continuously power driven member which through the interposed member effects the setting of the permutation setting frame.

While the invention has been referred to as applicable to telegraph transmitting and perfor-

rating apparatus, it is equally suitable for use in code translating telegraph keyboard apparatus.

In order that the invention may be clearly understood and readily carried into effect, some forms of construction in accordance therewith will now be more fully described by way of example with reference to the accompanying drawings, wherein:

Figure 1 is a partial side elevation of a keyboard transmitter for a start-stop telegraph apparatus;

Figure 2 is a perspective view of a part of the apparatus shown in Figure 1 making clear the action of the selector members;

Figure 3 is a perspective view showing the main parts of the transmitter; and

Figure 4 is a perspective view illustrating the application of a power actuated mechanism for the permutation setting frames.

In Figures 1 and 2, the permutation setting frames 1 are normally drawn upwards into the position shown, by tension springs 2, but when the frames 1 are operated they are pressed down and then slide on a pair of pins 3. Each of the frames 1 is extended at the foot and formed with a notch 4, but the notches of alternate frames face backward and forward as most clearly seen in Figure 2. These notches 4 are engaged by projections 5 and 5^a projecting on opposite sides from a horizontal lever 6 which, in fact, constitutes one of the set of selecting members. The levers 6 are pivoted on a common pivot 7 to a lever 8 mounted on a fixed pivot 9. It will be noticed that the projection 5^a on each selector lever 6 is further from the pivot 7 than the projection 5. The action of the shift key is to depress a pin 11 and swing a bell crank lever 12 downwards and backwards about its pivot 3. The bell crank 12 is pivoted at 13 to a connecting rod 14 which is also connected to the pivot 7 so that when the bell-crank 12 swings backwards, the common pivot 7 is also moved backwards and the spring 10 extended. During this action, the projection 5 is removed from the slot 4 at the lower end of one of the frames 1, while the projection 5^a moves into the slot or notch 4 of the frame 1 immediately to the front of that last-mentioned. Thus, the depression of the shift key moves all the selecting levers 6 into their rear positions. If now another character key 15 is depressed, its rear end 16 acts directly on the corresponding selecting lever 6 and the projection 5^a forces down the particular frame 1 with which it is engaging or if the shift key has not been depressed, the projection 5 presses down the adjacent frame 1. Thus, any character key 15, when depressed, may push down one or other of two permutation setting frames 1 depending upon whether the shift key has been depressed and has pushed back the selecting levers 6 or not.

When a frame 1 is thus drawn down, the notches or projections 17 thrust down certain of the five selecting vanes 18 which, in effect, constitute permutation members. The result is that certain of the five lower spindles 19 are rotated according to the particular character to be transmitted. The sixth vane 18^a controls the sending of the shift impulse and may be considered as a sixth selecting vane as it has an exactly similar effect to any one of the selecting vanes 18. The seventh or uppermost vane 18^b serves as a trip vane; it is actuated when any key is depressed to cause an additional frame 99 to be pushed down to trip the mechanism. The vane 18^b and additional frame correspond to and serve the same purposes as the vane 100 and frame 99 referred

to in the specification of my patent application Serial No. 24,153 filed May 29, 1935 and shown in Figures 1 and 2 of the drawings accompanying that specification except that the trip vane 100 in the prior application is placed below the five selecting vanes instead of above them. In the present case, upon the depression of any key, the vane 18^b is rocked by the actuation of the appropriate frame 1 and as in the prior application this results in pushing down the additional trip frame 99 against the tension of the spring 102 so that through the arm 103 a detent 104 is depressed, releasing the stop surface 105 and tripping the cam shaft 21 which will be referred to below.

The five vanes 18 on the spindles 19 extend through the frames 1 and into five additional frames 20 also capable of sliding up and down. Thus, when any vane 18 is rotated it pushes down the corresponding frame 20 and the code permutation corresponding to the character to be sent is thus set on the five frames 20 owing to the fact that some of these five frames will normally be in the upper position and some in the lower position.

A cam shaft 21 is rotated once for each character transmitted and it rocks first of all the lever 22 pivoted at 23 in a clockwise direction. The lever 22 carries at its upper end loose on a spindle 23^a a series of five arms 28, each provided with a forwardly extending tooth 24 and upper and lower projections 26 and 27. Thus, when the lever 22 is rocked, each tooth 24 first comes forward and passes above or below a central projection 25 on the respective permutation frame 20, thereby ensuring that each of those frames is moved fully upwards or downwards depending upon the code setting. As the lever 22 continues to move, the upper arm 26 or the lower arm 27 comes into contact either with the upper projection 20^a or the lower projection 20^b of the respective frame 20. In the former event, the particular lever 28 is rocked down into the position shown against the lower stop 28^a, but if the particular frame 20 is in the upper position, then the lower projection 20^b acting on the projection 27 turns the arm 28 against the upper stop 28^b.

As a result, each of the arms 28 has its tail end rocked up or down in accordance with the code permutation set and then acts through a rocking member 29 to move the corresponding selector bar 30 to the right as shown or to the left if the arm 28 is moved upwards.

Thus, by the mere depression of a key 15 and the shift key if necessary, a combination is set by the positions of the five selector bars 30 which corresponds to one or other of the characters which the particular key 15 represents.

In Figure 4, a power mechanism is shown for setting the permutation setting frames 1. These frames with their projections 17 and the vanes 18 on the spindles 19 are as shown in Figure 1 and furthermore, the selecting levers 6 have projections 5 and 5^a extending in opposite directions, the shift key mechanism for swinging the arm 8 and the common pivot 7 being omitted in Figure 3.

The power mechanism consists of a continuously driven ratchet 31 and a pawl 32 pivoted at 33 so that it can be rocked when a key lever 15 is depressed owing to the projection 34 engaging the tail of the pawl 32. In this way, the point of the pawl 32 is brought into engagement with the teeth of the ratchet 31 so that the latter carries round to some extent the pawl 32.

32 and the pivoted member 35, the latter turning clockwise about its pivot 36, and, through the connecting link 37^a, drawing down the corresponding selector lever 6 which acts in a way 5 similar to that shown in Figure 1. This goes on until the tail 37 of the pawl 32 comes into contact with the common throw-off bar 38. By this means the point of the pawl 32 is drawn out of engagement from the teeth of the ratchet 31 by the spring 39; then the member 35 is also 10 swung back about its pivot 36 by its spring 40. Here again the projection 5 or the projection 5^a draws down the corresponding frame 1 depending upon the operation of the shift key.

15 It may be desired to provide mechanical reaction against the depression of a key, in which case, suitable cam and lever mechanism 106, 107 shown in Fig. 3, is conveniently provided and arranged in such a way that at a definite time 20 period following the release of the cam shaft 21 (Figures 1 and 3), it actuates through the lever mechanism the universal trip frame 99 and vane 18^b positively, thus returning them to their normal or initial position. This may be achieved 25 in a simple manner by arranging the lever 107 actuated by a suitable cam 106 on the shaft 21 to act upon the trip frame 99 so that after the shaft 21 has turned through a predetermined angle from the position shown in Fig. 3, the last- 30 mentioned cam 106 comes into operation and rocks the said lever 107 which lifts the said trip frame 99 corresponding to the trip frame 99 shown in Figure 2 of the drawings accompanying the specification of my prior application. 35 Thus that trip frame 99 is moved upwardly back into its normal position, since in the example illustrated the trip frame is moved downwards when actuated by the universal trip vane 18^b.

With the above arrangement, it may be further arranged for the cam shaft 21 to be arrested for any convenient period at that angular position in its movement when it has returned the trip vane 18^b back into its normal position. For this purpose, as shown in Figure 3, a stop 40 surface 108 is secured on the shaft 21 and is arranged to be engaged by a lever 109. The latter is held up to engage surface 108 by a spring 110 until released at the desired instant by a cam 111 fixed to the selecting cam shaft 45 112 corresponding to the shaft 1 shown in Figures 1, 2 and 2a of the drawings of my said application Serial No. 24,153. The arrangement is such that until the cam shaft 21 is released to move away from the angular position in which 50 it is arrested by the engagement of the stop surface 108 by the lever 109, the universal trip vane 18^b is positively locked by the cam 106, so that it cannot be further operated by depressing one of the keys.

60 I claim:—
1. A permutation-setting mechanism for telegraph keyboard apparatus, comprising in combination, a plurality of pivoted single permutation members, a plurality of permutation-setting members each disposed and shaped respectively to engage directly a plurality of said permutation members on one or the other side of the pivots thereof to set same positively and selectively and a keyboard mechanism adapted to be 65 mechanically coupled to said permutation-setting members.

2. A permutation-setting mechanism for telegraph keyboard apparatus comprising in combination, a plurality of vanes mounted to turn 70 about their pivots, a plurality of permutation-

setting members each disposed and shaped respectively to co-act directly with a plurality of said vanes on one or the other side of the pivots thereof to turn same positively and selectively to establish the permutation settings and a keyboard mechanism adapted to be mechanically coupled to said permutation-setting members. 5

3. A permutation-setting mechanism for telegraph keyboard apparatus comprising in combination, a plurality of vanes mounted to turn about their pivots, a plurality of slidably mounted open frames embracing said vanes and each internally shaped to engage a plurality of said vanes directly on one or the other side of the pivots thereof to set same positively and selectively and a keyboard mechanism adapted to be mechanically coupled to said frames. 10

4. A permutation-setting mechanism for telegraph keyboard apparatus comprising in combination, a plurality of pivoted single permutation members, a plurality of permutation-setting members disposed respectively to engage directly said permutation members on either side of the pivots thereof to set same positively and selectively, a power-driven element, a plurality of actuating members each in operative relationship with one of said permutation-setting members, a keyboard mechanism including a plurality of pivoted keybars and means for selectively coupling said actuating members to said power-driven element under the control of said keybars. 15

5. A permutation-setting mechanism for telegraph keyboard apparatus comprising in combination, a plurality of vanes mounted to turn about their pivots, a plurality of slidably-mounted open frames embracing said vanes and internally shaped to engage certain of said vanes directly on either side of the pivots thereof to set same positively and selectively, a power-driven rotary element, a plurality of pivotally-mounted actuating members each linked to one of said frames, a keyboard mechanism including a plurality of pivoted keybars and a plurality of pawls each in operative relationship with one of said keybars and each adapted to couple one of said actuating members to said power-driven element. 25

6. A keyboard-controlled telegraphic apparatus comprising in combination, a plurality of permutation-setting members, a shift key, a plurality of selector members each mounted to move selectively into one of two positions under the control of said shift key and shaped to co-act with one of said permutation-setting members when in one of its positions and to co-act with another of said permutation setting members when in the other of its positions and a plurality of character keys each in operative relationship with one of said selector members to establish, through said selector member, the setting of one or other of a pair of said permutation-setting members. 30

7. A keyboard-controlled telegraphic apparatus comprising in combination, a plurality of permutation-setting members, a shift key, a pivoted lever located to be rocked from one position to another upon the actuation of said shift key, a spring-returned pivoted lever positively linked to said first-named pivoted lever, a common movable pivot pin carried by said second-named pivoted lever, a plurality of selector levers carried on said movable pivot pin and each shaped to engage one of said permutation-setting members when in one of its two positions and to engage another of said permutation-setting members when in the other of its two positions and a plurality of character keys, each in operative relationship with 35 40 45 50 55 60 65 70 75

- one of said selector levers to actuate the latter and thus to establish the setting of one or other of a pair of said permutation-setting members.
8. A keyboard-controlled telegraphic apparatus comprising in combination, a plurality of slidably-mounted permutation-setting frames arranged in pairs, the two frames of each pair being formed with oppositely directed notches, a shift key, a plurality of selector members each mounted to move selectively into one of two positions under the control of said shift key and each associated with a pair of said frames and shaped to engage the notches of said pair of frames when located in its two positions respectively, and a plurality of character keys each in operative relationship with one of said selector members to establish by the actuation of said selector member, the setting of one or other of said associated pair of frames.
9. A keyboard-controlled telegraphic apparatus comprising in combination, a plurality of permutation members formed as vanes mounted to turn about their pivots, a plurality of slidably-mounted open permutation-setting frames embracing said vanes and internally shaped to engage certain of said vanes directly on either side of the pivots thereof to set same positively and selectively, said frames also being arranged in pairs, the two frames of each pair being formed with oppositely directed notches, a shift key, a plurality of selector members each mounted to move selectively into one of two positions under the control of said shift key and each associated with a pair of said frames and each shaped to engage the notches of said pair of frames when located in its two positions respectively, and a plurality of character keys each in operative relationship with one of the selector members to establish by the actuation of said selector member, the setting of one or other of said associated pair of frames.
10. A permutation setting mechanism for an equal length code keyboard telegraph transmitter, comprising in combination, a plurality of code impulse vanes mounted to turn about their pivots and equal in number to the elements in a permutation to be set, a plurality of permutation setting members each disposed and shaped respectively to act on all of said code impulse vanes on one or other side of the pivots thereof, to turn same positively and selectively to establish the permutation settings, and a keyboard mechanism mechanically coupled to said permutation setting members.
11. A permutation setting mechanism for telegraph keyboard apparatus, comprising in combination, a plurality of vanes mounted to turn about their pivots, a plurality of slidably-mounted open frames embracing said vanes and each internally shaped to engage a plurality of said vanes directly on one or other side of the pivots thereof to set same positively and selectively, and a keyboard mechanism comprising a plurality of key levers directly mechanically connected to said frames.
12. A permutation setting mechanism for an equal length telegraph keyboard transmitter, comprising in combination, a plurality of permutation vanes mounted to turn about their pivots and equal in number to the elements in a permutation to be set, a plurality of movable permutation setting members each formed with a plurality of code projections, each located to coact positively with one of said permutation vanes on one or other side of the pivots thereof to determine the angular setting thereof, and a keyboard mechanism mechanically coupled with said permutation setting members.
13. A permutation setting mechanism for equal length code telegraph keyboard apparatus, comprising in combination, a plurality of vanes mounted to turn about their pivots and equal in number to the elements in a permutation to be set, a plurality of slidably mounted open frames each formed with a plurality of projecting snugs, each located to coact with one of said vanes on one or other side of the pivots thereof to determine the angular setting thereof, and a keyboard mechanism mechanically coupled to said slidably mounted frames.
14. Permutation setting mechanism for an equal length code telegraph keyboard transmitter, comprising in combination, a plurality of vanes mounted to turn about their pivots and equal in number to the elements of the code, a plurality of slidably mounted frames embracing said vanes, each character to be transmitted being allocated to one of said frames, and a keyboard mechanism mechanically coupled to said frames, each of said frames being formed with a plurality of snugs located to act on said vanes, some to turn the respective vanes clockwise and the others to return the remaining vanes counter-clockwise.

RONALD GEORGE GRIFFITH.
